UNITED STATES PATENT OFFICE.

GEORGE BELL, OF JESMOND, NEWCASTLE-UPON-TYNE, ENGLAND.

METALLIC ROPE.

Application filed December 30, 1921. Serial No. 525,904.

To all whom it may concern:

Be it known that I, GEORGE BELL, of Jesmond, Newcastle-upon-Tyne, England, a British subject, have invented certain new and useful Improvements in Metallic Ropes, of which the following is a specification.

The invention relates to wire ropes and has for its main object to provide a rope which will be practically immune from elongation under stress.

Broadly stated, the rope according to the invention comprises a plurality of parallel laid wires of any desired section which are mechanically compressed together and are then held together by a serving of metallic tape wound on hot and under tension, the tape being heated during application as by passing an electric current therethrough, or by other suitable heating means.

The rope may be composed of separate wires, or of a single wire wound to form a plurality of convolutions and joined at the ends, the convolutions being then closed together and bound by the tape intermediate of the ends so that loops are formed at the extremities.

In the accompanying drawings illustrating the invention Fig. 1 shows a length of rope partly in longitudinal section and partly in elevation.

Fig. 2 is a cross section on the line 2—2 of Fig. 1.

Fig. 3 shows in longitudinal section a rope formed of a single wire wound to form a plurality of convolutions and having loops at the ends, and

Fig. 4 shows to a larger scale the section of a preferred form of serving.

Referring to Figs. 1, 2 and 4 of the drawings, *a* designates the several parallel wires forming the core of the rope over which is wound on hot the serving *b* the latter being preferably of stepped section as shown best in Fig. 4, each convolution of the metallic tape overlapping the preceding convolution. To allow for expansion and contraction, a small clearance is provided during the winding as shown at *c*. As above described, the metallic tape *b* is wound on hot, the heating being preferably effected by causing an electric current to pass through it, and it is applied under tension in order to bind the compacted wires as tightly as possible before the cooling down of the metallic tape completes the process by contraction. Thus the metallic tape *b* also forms a

water tight casing for the wires *a* in addition to its binding action.

Referring to Fig. 3 the rope may, as shown, be composed of a plurality of convolutions of parallel wires produced by winding a wire around spaced rollers and then joining the ends of the wire. The two portions *k* *k*¹ thus produced are then bound together by the metallic tape in the manner above described, the winding terminating at such distance from the ends as to leave loops *e*. A splice is effected by means of split collars *f* clamped together by bolts *g* to grip the rope and the ends of the metallic tape *b*. The loops *e* are covered with a flexible wire *j*.

To prevent ingress of water between the rope and collar, the latter is bell mouthed as shown at *h*, and a seal is produced by brazing or filling the bell mouth with a suitable medium such as white metal.

What I claim as my invention and desire to secure by Letters Patent of the United States is:—

1. A rope comprising a core consisting of flattened convolutions of metal wire and a metal ribbon shrunk in spirals round said convolutions.

2. A rope comprising a core consisting of parallel metal wires and a metal ribbon shrunk in partly overlapping spirals round said parallel metal wires.

3. A rope comprising a core consisting of flattened convolutions of metal wire, said convolutions lying parallel to and adjacent one another except at their ends forming loops, and a metal ribbon shrunk in spirals round said parallel portions of said convolutions.

4. A rope comprising a core consisting of continuous flattened convolutions of metal wire, said convolutions lying parallel to and adjacent one another except at their ends forming loops, a metal ribbon shrunk in spirals round said parallel portions of said convolutions and flexible wires wound round the portions of said convolutions forming said loops.

5. A rope comprising a core consisting of continuous flattened convolutions of metal wire, said convolutions lying parallel to and adjacent one another except at their ends forming loops, a metal ribbon shrunk in overlapping spirals round said parallel portions of said convolutions, flexible wires wound round the portions of said convolutions forming said loops, and clamps sur-

rounding the junction of said loops so covered with said parallel portions of said convolutions so covered.

6. A rope comprising a core consisting of 5 continuous flattened convolutions of metal wire, said convolutions lying parallel to and adjacent one another except at their ends forming loops, a metal ribbon shrunk in partly overlapping spirals round said parallel portions of said convolutions with a clearance between the shoulder formed by the overlapping of one spiral over another and the edge of the next spiral, flexible wires wound round the portions of said convolutions forming loops, clamps surrounding the junction of said loops so covered with said parallel portions so covered, and means for preventing entry of water between said clamps and the surfaces surrounded thereby.
- 10 7. Method of manufacturing a wire rope consisting in arranging a series of parallel metal wires to form a core and winding a

metallic ribbon in a hot state and under tension in overlapping spirals round said parallel metal wires.

25

8. Method of manufacturing a wire rope consisting in winding a metal wire in a series of contiguous convolutions, pressing the convolutions together so as to form a series of parallel wires with a loop at each end winding a metallic ribbon in a hot state and under tension in overlapping spirals round said parallel wires, winding flexible wire round the convolutions of said loops, fixing clamps round the junctions of said parallel wires and said loops so covered, and rendering waterproof the joints between said clamps and the rope.
